CHLORINATOR UNIT

Nyyrikki K. Stenberg, Roslyn, Pa., assignor to Capital Controls Co., Inc., Colmar, Pa., a corporation of Pennsylvania

Filed July 3, 1968, Ser. No. 12,621

Term of patent 14 years

U.S. Cl. D23—3

Int. Cl. D23—01

Fig. 3

Fig. 4

FIG. 1 is a front perspective view of a chlorinator unit embodying my new design;

FIG. 2 is a top plan view of the chlorinator unit shown in FIG. 1;

FIG. 3 is a left-side elevational view of the chlorinator unit shown in FIG. 1;

FIG. 4 is a rear elevational view of the chlorinator unit shown in FIG. 1;

FIG. 5 is a fragmentary transverse sectional view taken generally along the line V—V of FIG. 1.

The broken lines are shown for illustrative purposes only.

I claim:

The ornamental design for a chlorinator unit, as shown and described.
